D238,615 S 1/1976 Maier

FIG. 1 is a perspective view of a device for protection against x-rays according to a first embodiment of my design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a device for protection against x-rays according to a second embodiment of my design;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

The broken lines showing environment or structure (e.g., stitching) are for illustrative purposes only and form no part of the claimed design.

1 Claim, 6 Drawing Sheets
